UNITED STATES PATENT OFFICE

141,914

DESIGN FOR A FLUID STORAGE TANK

Ernest H. Benson, Kansas City, Mo.

Application February 23, 1945, Serial No. 118,095

Term of patent 14 years

(Cl. D91—1)

To all whom it may concern:

Be it known that I, Ernest H. Benson, a citizen of the United States, residing at Kansas City, in the county of Jackson and State of Missouri, have invented a new, original, and ornamental Design for a Fluid Storage Tank, of which the following is a specification, reference being had to the accompanying drawing, forming part thereof in which

Fig. 1 is a plan view of a tank showing my new design,

Fig. 2 is a side elevational view,

Fig. 3 is an end elevational view.

I claim:

The ornamental design for a fluid storage tank, as shown.

ERNEST H. BENSON.
